FIG. 3.

UNITED STATES PATENT OFFICE

2,275,564

VENTILATOR

Sam F. Shawhan and Constant E. Nicolet, Syracuse, N. Y., assignors to Carrier Corporation, Syracuse, N. Y., a corporation of Delaware

Application December 2, 1938, Serial No. 243,503

6 Claims. (Cl. 98—94)

This invention relates to air circulating apparatus and more particularly to air circulating and ventilating units.

The general object of the invention is to provide an improved air circulating and ventilating unit of the type adapted to be positioned in a window opening or the like, of an enclosure, which by reason of its unique design affords various advantages over devices heretofore known.

Thus, an object of the invention is to provide an air circulating unit which is adapted to discharge into an enclosure either recirculated air withdrawn from the enclosure or outdoor air withdrawn from the outdoor atmosphere, or a mixture of recirculated and outdoor air in any desired proportions.

It is another object of the invention to provide an air circulating and ventilating unit which removes dust, pollen, grime and other foreign matter from all air discharged from the unit, regardless of whether the discharged air is drawn from the outdoor atmosphere, or from the enclosure served by the unit, or from both.

It is another object of the invention to provide an air circulating and ventilating unit of the type adapted to be positioned in a window opening which is weatherproof and which may be sealed effectively against the entrance of air from the outdoor atmosphere whenever this is desired, thus to prevent the infiltration of outdoor air into the enclosure and to provide positive protection against the action of strong winds or the like.

It is another object of the invention to provide an air circulating and ventilating device adapted to be positioned in the window opening of an enclosure which is itself extremely quiet in operation and which additionally serves to minimize the transmission of noises from the outdoor atmosphere to the enclosure served by the device.

It is another object of the invention to provide an air circulating and ventilating unit of the window type which assures a constant and positive circulation of air, free from drafts, and at a rate which may be varied in accordance with the requirements of particular installations or to suit personal preferences.

Still another object of the invention is to provide an air circulating and ventilating apparatus which is relatively simple in design, inexpensive to construct and operate, and which is reliable and efficient in operation; which is complete, compact, and self-contained; and which may be installed quickly and easily in any desired loca-

tion, and readily removed for reinstallation in any other desired location.

A feature of the invention resides in the provision of a ventilating and air circulating device of the type adapted to be positioned in the window opening or the like of an enclosure, which is provided with an inlet for recirculated air drawn from the enclosure, an inlet for outdoor air withdrawn from the outdoor atmosphere, and a device for regulating the proportions in which air is drawn through each of these inlets for delivery to the enclosure, said device being arranged to provide for air flow through one or the other of said inlets exclusively, should this be desired.

Another feature of the invention resides in the provision of an air circulating and ventilating unit provided with a recirculated air inlet, an outdoor air inlet communicating with the outdoor atmosphere, and means for passing air from both of said inlets through a filter adapted to remove foreign matter therefrom, the air then being discharged into the enclosure in an upward direction in such manner as to provide an active circulation of air therein without objectionable streaks or drafts.

Other objects, features and advantages of the invention will be more apparent from the following description, to be read in connection with the accompanying drawings, in which:

Fig. 1 is a view in perspective of a ventilator unit embodying the invention in a preferred form;

Fig. 2 is a front elevational view of the unit of Fig. 1, partly broken away to show portions of the interior thereof;

Fig. 3 is a sectional view, taken on the line 3—3 of Fig. 2;

Fig. 4 is a sectional view, taken on the line 4—4 of Fig. 2; and

Fig. 5 is a fragmentary view, taken on line 5—5 of Fig. 2, and illustrating the mechanism for operating the proportioning damper.

Referring now to the drawings, similar designations referring to similar parts, numeral 10 designates generally a cabinet of generally elongated configuration and adapted to be positioned in a window opening or the like of an enclosure. When the unit is positioned as intended, the front portion 11 thereof will extend from the window into the enclosure to be served thereby while the rear portion 12 will extend rearwardly of the window opening into the outdoor atmosphere. Extending along the top and down the sides of the cabinet 10 there is preferably provided a sealing strip 13 of suitable resilient material, such as

rubber or the like, preferably received within a containing channel 14. Thus when the window with which the unit is associated is closed, the lower portion of the window sash will engage the sealing strip 13 to form an effective air seal. If desired, there may be provided suitable filler strips of a type well known in the art for filling up the space between the sides of the cabinet and the sides of the window opening. Preferably, these filler pieces are adjustable. Since various devices of this character are well known and understood in the art, no further description thereof is deemed required here, it being sufficient to understand that they effectively prevent the passage of air between the enclosure and the outdoor atmosphere.

The front wall 15 of the cabinet is preferably curved, as best seen in Figs. 1, 3 and 4. The lower portion of the front wall 15 is provided with a griled recirculated air inlet opening 16 while the upper portion of the front wall 15 is provided with one or more suitably griled outlet openings 17. As illustrated, two outlet openings 17 are employed, but it will be understood that, if desired, a single outlet opening, or any desired number thereof, may be employed. Preferably, both the recirculated air inlet opening 16 and the air discharge opening 17 extend substantially completely throughout the length of the cabinet 10.

It will be observed that the recirculated air opening 16, because of the contour of the front plate 15, tends to draw air upwardly into the cabinet, whereas the air discharge openings 17, because of the configuration of the front plate 15, tend to discharge air upwardly from the unit. This formation of the inlet and discharge openings therefore tends to initiate and foster an active rotary circulation of air throughout the enclosure served by the unit. Further, it will be noted that the air which is delivered from the unit in an upward direction is caused to mix with and be attemperated by the air in the enclosure, so that before the introduced air enters the zone of occupancy its velocity and condition have both been tempered. Thus despite the active circulation of substantial quantities of air, the unit provides freedom from drafts, streaks and the like, and on the contrary gives assurance of positive, healthful and comfortable air circulation at all times.

Extending lengthwise of the unit throughout the length thereof is a horizontal partition 18 which extends from the front plate 15, at a point above the recirculated air inlet 16, rearwardly of the unit, the partition terminating a substantial distance from the rear of the unit. The partition 18 may be supported in any desired manner, but preferably is supported by being welded or similarly secured to the end walls of the cabinet, the partition being free between the end walls of the cabinet.

Supported by the partition 18 centrally of the cabinet is a supporting platform 19 carrying brackets 20 which in turn support an electric motor 21. Positioned on either side of motor 21 is a fan rotor 22 supported and rotated by shaft 23 extending from the motor 21. Each fan rotor is contained within a fan scroll 24. The fan scrolls 24 are preferably provided with double inlet openings 25 for admitting air to the fan rotors. The fan scrolls 24 discharge through openings 26 formed in a partition 27 extending vertically from the partition 18 to proximate the

top of the cabinet, and extending substantially throughout the length of the cabinet.

The air discharged from the fans through openings 26 is delivered into a discharge chamber 28 formed between the front wall 15 and the partition 27. To provide for the deadening of noises which might otherwise be transmitted within the enclosure served by the unit, the walls of chamber 28 are preferably provided with suitable sound-absorbing material. Thus, the inside of the front plate 15 is preferably provided with a sound-absorbing packing or the like, designated 29, and a similar packing 30 is provided on the front side of the partition 27. The sound absorbers 29 and 30 are effective not only to minimize noises due to operation of the unit itself, but also prevent the transmission of noises coming from the outdoors. The silent operation of the unit is further enhanced by the free mounting of partition 18 as above described. Thus any vibrations due to operation of the motor and fan rotors are taken up by oscillation of the partition 18 between its ends, and these vibrations are prevented, in large measure, from being transmitted to the outer casing. Similarly, the supports 20 and the motor 21 are provided with suitable sound-absorbing cushions of any desired type.

The upper rear portion of the cabinet comprises a casing section designated 31 which is pivotally mounted in any desired manner at 32 and is adapted to be rotated rearwardly, as indicated in dotted lines in Fig. 4. The casing section 31 carries a pan-type support 33, which is preferably welded or otherwise suitably secured thereto, the support 33 serving to receive and contain a removable filter 34, which preferably extends throughout the length of the unit interior.

When the casing section 31 is in normal position, as seen in Figs. 1 and 3, the support 33 and removable filter 34 are snugly received between an upwardly extending portion 35 of partition 18 and an upwardly extending portion 36 of the plate forming the supporting platform 19. Thus portions 35 and 36 form an effective seal which prevents the passage of air through the rear of the cabinet and to the region of the fans, except through the filter 34.

It will be noted that the partition 18 provides a passage 37 for recirculated air which extends rearwardly of the cabinet from the recirculated air inlet opening 16, the passageway 37 being adapted to deliver air from the inlet 16 to the air supply chamber 38, from which chamber air is drawn through the filter 34 for supply to the area served by the unit. Also, it will be observed that the lower rear portion of the unit is provided with an outdoor air inlet opening 39, this opening being formed between the bottom wall 40 of the cabinet and the bottom of the rear wall 41 of the cabinet, the rear wall 41 comprising a part of the pivotally mounted casing portion 31. Thus upon operation of the fans 22, air may be drawn in to the cabinet from the enclosure served, through inlet 16, and also from the outdoor atmosphere, through inlet 39.

At times, it may be desired to circulate return air only and to prevent the admission of any outdoor air to the enclosure. At other times, it may be desired to circulate outdoor air exclusively, and not to recirculate any air from the enclosure. At other times, it may be desired to circulate both outdoor air and return air in varying proportions. To provide for desired con-

tro in all such cases, there is provided a damper 42 in the lower rear portion of the cabinet, pivotally mounted proximate the point at which passageway 37 approaches the outdoor inlet opening 39.

The damper 42 may be hingedly mounted in any desired manner, but it is preferred to provide a U-shaped channel 43 within which an extending lip 44 of the damper 42 is received. This construction provides a freely acting hinge mounting for the damper and at the same time the U-shaped channel 43 provides an effective air seal. Further, the hinge structure is effectively protected against the elements. The damper 42 is so formed that when the top of the damper is moved toward the front of the cabinet, the top of the damper will abut the extension piece 35, so that if the damper is moved to the maximum forward position, it will serve completely to interrupt the flow of air through inlet opening 16 and passageway 37, and will cause outdoor air exclusively to be supplied to the fans for delivery to the enclosure served. Conversely, if the top of the damper 39 is moved to the maximum position rearwardly of the cabinet, its top flange 45 will abut a resilient sealing strip or the like 46, mounted on a flange at the bottom of rear wall 41, and thus will cause complete interruption of the supply of outdoor air to the cabinet, and will result in the circulation of return air exclusively. When the damper is in intermediate positions, both return air and outdoor air will be circulated by the unit, the proportions of outdoor air and return air being dependent upon the position of the damper in each case.

The damper 42 is preferably regulated in position by means of a lever 47 extending outside the cabinet and adapted readily to be rotated by an operator. The lever 47 is connected to a link 48 which controls the position of control bar 49 pivotally connected to the damper 42, as indicated at 50. It will be apparent that when the top of the lever 47 is pushed toward the rear of the cabinet the damper will be moved toward the position in which it permits maximum recirculation of return air, while when the top of lever 47 is moved toward the front of the cabinet the damper will be moved into position in which it affords a maximum supply of outdoor air to the fans of the apparatus.

In ventilator units heretofore known, a common shortcoming has been the inadequacy of these units to prevent the entrance of outdoor air when this was not desired. It will be noted that when the damper 42 of the present construction is positioned to cut off the supply of outdoor air, there is provided an effective seal both at the bottom of the damper, by means of the channel 43, and at the top of the damper, by means of the flange 45 and the sealing member 46. Further, when the opening 39 is completely closed by damper 42, the movement of the damper into this extreme position throws the damper off-center so far as its pivotal mounting in the channel 43 is concerned. Hence, the effective seals of the channel 43 and the flange 45 continue to prevent the ingress of outdoor air even though there be exerted a substantial wind force on the damper 42, for the off-center position of the damper will cause a locking action sufficient to prevent such undesired opening of the damper 42.

Because of the protected location of the outdoor inlet 39, there is little opportunity for rain, 75

snow or the like to enter within the cabinet but since small quantities of water may collect in the cabinet from time to time due to unusual circumstances, there is preferably provided a small drain opening 51 in the bottom wall 40 of the cabinet.

To insure the stable positioning of the cabinet within all types of window openings, regardless of the formations of the window sills, there are 10 preferably provided two or more adjusting screws 52 extending through openings in the partition 18 and extending through suitable threaded openings in the bottom wall 40 of the cabinet. Thus, if the outer window sill at which the cabinet is installed slopes downwardly sharply from the region of the window sash, the screws will be extended downwardly a substantial distance below the bottom wall 40 of the cabinet, in order to provide the desired support. If the window sill is relatively flat, however, it will be understood that the desired support may be obtained by adjusting the screws 52 in such manner that they extend only slightly below the bottom wall 40 of the cabinet.

25 Although any type of inlet and discharge grilles may be utilized in conjunction with the invention, it is preferred that the air discharge outlet 17 be provided with adjustable vanes 53. While the adjustable vanes 53 may be of any desired type and may be individually mounted, it is preferred that they be interconnected so that by adjustment of a single operating lever 54, the discharge direction of an entire set of vanes may be regulated to provide for discharge of air from 30 the unit in the desired direction.

35 While the housing of the apparatus may be fabricated in any desired manner, the preferred construction embraces the bending of the top wall of the housing to provide a downwardly extending flange 55. Also, there is welded to the top wall of the housing a channel 56 so positioned that one of the legs 56a of the channel abuts the downwardly extending portion 55. The top of partition 27 is slightly bent over upon itself and a bolt 57 is used to connect the channel leg 45 56a with the bent-over portion of partition 27. This construction is preferred since it eliminates the necessity for using screws or bolts which would be visible through the discharge grilles 17. In the construction illustrated, nothing is visible 50 inside the chamber 28 except the uniform surface of the sound absorber 30.

55 While any suitable arrangement may be employed for controlling the operation of the fan motor 21, it is preferred to provide a rheostat 58 under the control of knob 59 for controlling the speed of the fan motor, thus to provide for desired control of the rate at which air is discharged from the unit. An electrical extension plug 60 is provided for plugging in the electrical circuit of the unit to any suitable source of electrical energy.

60 It will be observed that the unit is entirely self-contained and thus may be installed quickly and readily wherever desired, and may also be removed readily whenever this is desired.

65 It will be appreciated, further, that the pivotal mounting of the casing portion 31 permits convenient access to all portions of the interior of the unit. Thus it permits the filter 34 to be removed and replaced as required with great facility, and permits access to the stabilizer screws 52.

70 Since many changes may be made in the invention without departing from its scope, it is

intended that all matter contained in the above description or shown in the accompanying drawings shall be interpreted as illustrative only and not in a limiting sense, applicants limiting themselves only as indicated in the appended claims.

We claim:

1. A window ventilator comprising a casing having a front stationary section and a rear section swingable about hinged mounting means, a return air inlet formed in the front section of said casing proximate the lower portion thereof, the portion of the wall of said casing in which said inlet is formed being at an acute angle with respect to a horizontal plane, an outdoor air inlet formed in said casing at the rear thereof beneath the hinged rear section, filter means in the hinged rear section, means providing a common passage for communication between said return air inlet and said filter and said outdoor air inlet and said filter, whereby air may be supplied from both of said inlets to said filter, blower means for drawing air through said filter, and a discharge outlet in the same wall in which said return air inlet is formed adapted to discharge air from said casing in an upward direction into the area served by the apparatus.

2. A window-type air circulating and ventilating unit comprising a casing, a return air inlet extending upwardly at an acute angle to the horizontal through the front wall of said casing proximate the lower portion thereof to draw the air upwardly into the casing, said inlet extending substantially throughout the length of said casing and a discharge air outlet formed in said front wall adapted to discharge air from the casing in an upward direction, an outdoor air inlet formed between two portions of said casing at the rear thereof and extending substantially throughout the length thereof, filter means, means providing communication between said return air inlet and said filter means and said outdoor air inlet and said filter means, whereby air may be supplied from both of said inlets to said filter means, blower means for drawing air through said filter means, and a discharge outlet adapted to discharge air from said casing into the area served by the apparatus, the blower being located between the filter and the discharge outlet, said discharge outlet extending substantially throughout the length of said casing.

3. A window-type air circulating and ventilating unit according to claim 2 in which the rearward portion of said casing is pivotally mounted upon and with respect to the remainder of said casing,

the outdoor air inlet being formed between the rear lower fixed air inlet being formed beneath the rear lower fixed portion of the casing and the rear lower pivoted portion of the casing, said filter means being removably mounted within said rearward pivoted portion of said casing, whereby when the rearward portion of the casing is pivoted away from the remaining portion of the casing, the filter may readily be removed and replaced.

4. A window-type air circulating and ventilating unit including a casing having an air inlet formed proximate the front bottom portion thereof, a rear bottom portion in said casing, an outdoor air inlet formed proximate the rear bottom portion, partition means separating the interior of said casing into an upper and a lower section, said partition means extending rearwardly to a point proximate but spaced from the rear of said casing and forming in combination with the bottom of said casing an air passageway adapted to receive air from said return air inlet opening, fan means and driving means therefor mounted on and positioned above said partition means, a filter positioned rearwardly of said fan means and said fan driving means in spaced relation from the rear wall of said casing, said filter being in the path of air passing to said fan means from said passageway and from said outdoor air inlet opening, and means forming an upwardly extending discharge passageway adapted to receive air from said fan means and to discharge such air into the area served by the unit, other partition means to one side of said fan means segregating the front wall of said casing from said fan means, said fan driving means and said filter, said discharge passageway extending substantially throughout the length of the apparatus and being formed between the front wall of said casing and said other partition means.

5. A unit according to claim 4 in which a rear portion of said casing is pivotally mounted upon and with respect to the remaining portion of said casing, and in which said filter is mounted within said rear casing portion, so that by pivotal adjustment of said rear casing portion said filter may readily be withdrawn and replaced.

6. A unit according to claim 4 characterized by the fact that said outdoor inlet opening is formed between the rear bottom portion of the casing and the lower edge of the pivoted portion of the casing.

SAM F. SHAWHAN.
